PROCESS FOR TREATING HYDROCARBONS

Original Filed June 1, 1920 2 Sheets-Sheet 2

UNITED STATES PATENT OFFICE

LESTER KIRSCHBRAUN, OF LEONIA, NEW JERSEY, ASSIGNOR TO UNIVERSAL OIL PRODUCTS COMPANY, OF CHICAGO, ILLINOIS, A CORPORATION OF SOUTH DAKOTA

PROCESS FOR TREATING HYDROCARBONS

Application filed June 1, 1920, Serial No. 385,462. Renewed June 2, 1927.

This invention relates to improvements in process for treating hydrocarbons, and refers more particularly to a process in which relatively heavy petroleum oil, such as gas oil, has a substantial percentage thereof cracked into light gasoline like bodies. The process is of the so called continuous type in which the oil is, or may be, fed through relatively small closed coils in the heating or cracking zone, and then passes to a larger and preferably an elongated expansion or vapor chamber or chambers.

As is well known, one of the particular difficulties still experienced in cracking petroleum oil, is the clogging up or burning out of the apparatus due to carbon formation on the walls of the tubes; this is more particularly true where vaporization takes place.

As an object of the present invention, I propose to eliminate or greatly reduce the crustation formation of carbon in the vapor chamber by injecting heated fresh oil from the heating zone at various points in the elongated expansion chamber. This will insure there being at all times a sufficient amount of liquid in all parts of the vapor chamber to sweep out, or carry along the carbon through the residue line. It is well known that oils from different fields act differently when cracked, with reference to their carbon deposits, and it may be desirable to vary the amount of oil injected into various parts of the vapor chamber, not only with reference to the character of the oil treated, but in different stages of the same operation. For example, it may be desirable to increase the amount of oil in the forward or delivery ends of the vapor chamber toward the end of the run.

It is to be understood that the vapors which pass out of the vapor chamber are subjected first to a reflux condensing action and thence to a final condensation, while the residue is constantly drawn off as the process

and returned directly to the inlet side of the heating tubes.

In the drawings:

Fig. 1 is a plan view, and Fig. 2 a side elevation of my apparatus.

Referring in detail to the drawings, 1 designates the furnace in which is supported the heating coil 2 which forms the cracking zone. This coil may consist of 160 feet of four-inch pipe, and the inlet side of which is connected to a charging pump 3 leading to any suitable source of supply. Mounted in a suitable setting 4 is the vapor or reacting chamber 5, which may take the form of 80 feet of twelve-inch pipe. The hot oil passes through manifold line 6 and branches 7, 8, 9 and 10, to each of the tubes of the vapor chamber. A throttle valve 11 is interposed in each of the branches 7, 8, 9 and 10, whereby the amount or percentage of oil passing to any tube of the vapor chamber may be controlled at will. The residue is drawn off by line 12 controlled by valve 13 to any suitable receiver. A valve 14 is interposed at the entrance to the manifold 6. This valve is preferably left wide open, but may, if desired, be more or less throttled to produce a differential pressure in the system.

The vapors pass out of the reacting chamber through risers 15, which are connected to an aerial condenser 16. The vapors which are condensed in the reflux 16, pass back through lines 17 and 18 to the pump 3, where they are mixed with the fresh charging stock. The incondensable gas and uncondensed vapors pass to a water condenser 19 and thence to a receiver 20. This receiver 20 is provided with liquid draw-off line 21, controlled by valve 22 and gas draw-off 23 controlled by valve 24.

In carrying out the process in the early part of the operation, 65% of the oil may pass through the pipe 7, 15% through the pipe 8, 12% through the pipe 9, and 8% through pipe 10. In the latter part of the run 40% of the

oil may pass through the pipe 7, 25% through pipe 8, 20% through the pipe 9, and 15% through the pipe 10.

It is to be understood that these percentages are merely illustrative and will vary with the character of the pressure distillate and end point gasoline desired, as well as the character of the charging stock. Starting with a gas oil of 32° Baume from a Kansas field, the oil temperature in the cracking zone might be 750° to 800° F., and the pressure 100 pounds. 65% of the oil can be converted into pressure distillate of 51° Baume gravity, yielding 35% of gasoline of 400 end point, this percentage being based on total charging stock.

As above stated, this run is merely illustrative of one manner of carrying out the invention. No hard and fast limits can be given for different kinds of oil being treated, and this, of course, varies still more where different end points, or different percentages of pressure distillate are desired.

Particular advantages of this method of supplying oil to a vapor or reacting chamber reside in the fact that heat losses through conversion and vaporization of the lighter hydrocarbons are replenished by the introduction of adjusted quantities of heated oil from the heating zone at suitable intervals. The introduction of oil from the heating zone in one place necessitates an excess of heat in the cracking tubes in order to provide the heat necessary for conversion and vaporization and a consequent drop of temperature of the oil through the vaporizing tubes. As a result of this excessive heat, carbon is frequently produced in unusual quantities, in the latter elements of the heating tubes. By the described method of introducing the hot oil, a mild degree of heat can be employed, thereby eliminating difficulties attending this excessive heating in the cracking zone.

Also the introduction of the hot oil at predetermined intervals to the vapor zone at points where the introduction is deemed essential, lends itself to the increasing of the temperature of the oil in the vapor zone to maintain a more constant temperature in this zone and prevent thereby excessive loss through the formation of incondensable gas and carbon.

I claim as my invention:

1. A process of cracking oil, consisting in passing a stream of oil through a cracking furnace where said oil is subjected to a cracking temperature, in then delivering the oil to a reacting stage comprising connected chambers, in introducing different proportions of said oil into different reacting chambers at points intermediate the length of the reacting stage, in taking off vapors from said chambers for condensation and collection, and in maintaining a superatmospheric pressure on the system.

2. A process of cracking oil, consisting in

passing a stream of oil through a cracking furnace where said oil is subjected to a cracking temperature, in then delivering the oil to a reacting stage comprising connected chambers, in introducing different proportions of said oil into different reacting chambers at points intermediate the length of the reacting stage, in discharging vapors from said reacting stage to a reflux condenser, in returning reflux condensate for repassage through the cracking furnace, in withdrawing residue from said reacting stage, and in maintaining a superatmospheric pressure on the system.

LESTER KIRSCHBRAUN.
